UNITED STATES PATENT OFFICE.

BENJAMIN B. RHYNE, OF CHARLOTTE, NORTH CAROLINA.

PUMPING DEVICE.

1,243,222.

Specification of Letters Patent. Patented Oct. 16, 1917.

Application filed October 15, 1915. Serial No. 56,085.

To all whom it may concern:

Be it known that I, BENJAMIN B. RHYNE, a citizen of the United States, residing at Charlotte, in the county of Mecklenburg 5 and State of North Carolina, have invented new and useful Improvements in Pumping Devices, of which the following is a specification.

The invention relates to an improved air 10 pump or motor adapted particularly to be operated by compressed air and designed to actuate a liquid pump, the construction being particularly directed to automatic controlling means for accommodating the pump 15 and governing its operation.

The improved motor is of the reciprocating type and operated by compressed air from a suitable source, the delivery of the power medium on opposite sides of the piston 20 ton being automatically controlled in the operation of the motor, and the delivery of the motive fluid from the compressor or storage tank to the motor is in turn automatically controlled by a desired condition 25 of the fluid being pumped, whereby the pump is automatic in all operations.

The invention in the preferred form of details will be described in the following specification, reference being had particularly to the accompanying drawings, in which:

Figure 1 is an elevational view of the apparatus;

Fig. 2 is a vertical sectional view of the 35 motor;

Fig. 3 is an elevation of one section of the casing of the slide valve;

Fig. 4 is a similar view of the other side of the casing;

Fig. 5 is a horizontal section through the slide valve;

Fig. 6 is a vertical section of the controlling valve;

Fig. 7 is a section on line 7—7 Fig. 6;

Fig. 8 is an elevation of the equalizing lever;

Fig. 9 is a plan view of the same;

Fig. 10 is a transverse section on the line 10—10 of Fig. 9;

Fig. 11 is a broken sectional view illustrating the connection of the levers;

Fig. 12 is a side elevation of the slide valve.

From the accompanying drawing it will 55 be noted that the improved structure includes a pump or air motor comprising a

cylinder 1 having heads 2 and 3, the latter being suitably formed for the reciprocation therethrough of a piston rod 4. The piston rod at the end within the casing terminates 60 in a head 5 and on the rod immediately beneath the head is secured a piston 6 having oppositely acting piston cups 7. The piston is shown and is preferably constructed in two parts, with the oppositely turned cups 65 secured to each respective part, the usual expansion rings 8 being arranged to hold the cup in proper contact with the wall of the piston. The air motor described is designed to operate a water pump of any suitable 70 type connected to the piston rod 4.

The piston rod is formed with two ducts 9 and 10 extending longitudinally thereof, the former opening laterally through the piston rod at a point immediately below the 75 piston 6 while the latter extends through the piston rod and through the head 5 to open on the opposite side of the piston.

Secured upon the piston rod below the cylinder and at the lower termination of 80 the ducts 9 and 10 is what I term a slide valve involving opposing casings of a solid type as 11 and 12, secured together in any appropriate air tight manner. The section 11 of the casing which represents one wall 85 thereof is formed with a block extension 13 having at the outer surface thereof an opening 14 in the form of a nipple for a purpose which will later appear. Arranged vertically of the section 12 is a rounded opening 15 to 90 receive the piston rod, a cap plate 16 being secured upon the section 12 and formed in its inner surface with a depression 17 to complete the piston rod receiving opening, the cap plate being bolted to the slide valve, 95 as shown. Arranged intermediate the sections 11 and 12 is a slide or valve plate 18, which plate is formed with an ear extension 19 secured upon a stem 20 which projects through the sections of the slide valve 100 and beyond one side surface thereof, as shown. The section 11 of the slide valve is formed with spaced channels 21 which at their outer end communicate with the supply nipple 14, while the section 12 of the 105 slide valve is also formed with spaced channels 22 which communicate at all times with lateral openings 23 from the respective ducts 9 and 10 of the piston rod. The valve plate 18 is provided with two openings 24 so arranged that in the respective positions of said plate, at least one of the openings 24

will be in communication with the channels 22 of the section 12. The section 11 of the slide valve is also provided with exhaust openings 25 which lead directly to the atmosphere. The disposition of the openings 24 is such that in one position of the valve plate there will be provided an uninterrupted communication between one of the channels 21 and the underlying channel 22 of the section 12, while at the same time the remaining channel 22 of the section 12 will communicate through another of the openings 24 with the exhaust opening 25 of the section 11. As the valve plate, as will hereinafter appear, is adapted for two positions, it will be obvious that air from the supply nipple will be alternately admitted, through the ports 9 and 10, the charging port being thus supplied with pressure while the remaining port is open to the exhaust.

The slide valve is secured upon the piston rod below the cylinder, the latter for this purpose being supported upon uprights 26 rising from a suitable base 27. On one of the uprights are arranged trips 28 at the respective limits of movement of the slide valve and adapted in operation to trip the valve plate to change its operative positions. For this purpose the stem 20 which is secured to the valve plate as previously described is provided with a trip lever 28' extended beyond the slide valve and having projection 29 to be engaged by the pins 28. The spring 31 is connected to the trip lever 35 and to the bracket 32 extended from the opposite side of the slide valve, the spring exerting a pull upon the valve plate in both directions, it being understood that the movement of the trip pin in either instance 40 throws the trip lever beyond a position aligned with the spring so that the spring operates to pull the valve plate to operative position in either direction, the trip pin serving to initially start the lever while 45 the spring rapidly completes the movement and sets the plate.

As a means for controlling the admission of air to the slide valve and therefore controlling the operation of the pump, I provide what I term a controlling valve comprising a two-part casing 33, 34, presenting a chamber 35 within which is arranged a diaphragm 36 secured at its edges between the edges of the casing sections, as shown. 50 The diaphragm is preferably constructed to provide a lower brace section 37 and an upper rubber section 38. A valve stem 39 extends through the diaphragm, being fixed thereto and the movement of the diaphragm 60 is tensioned in one direction by a spring 40, as will be plain from the drawings. Secured below the casing is a valve chamber 41 in which the valve stem 39 extends. The valve chamber is secured to the casing of the controlling valve and a rubber gasket or

diaphragm 42 is arranged in an appropriate recess and about the valve stem to prevent passage of air to the lower side of the diaphragm 36. The valve chamber is provided with an inlet port 43 closed by a valve 44 carried upon the lower end of the stem 39 and with a lateral port 45 which communicates through a hose or other flexible connection 46 with the inlet nipple 14 of the slide valve.

Assuming the pump to be used in connection with the water supply, the water pipe 47 through which the fluid is delivered as a result of the pumping operation, has arranged in open communication therewith an air chamber 48. From the upper end of the chamber extends a pipe connection 49, valve controlled as desired, and opening into the upper end of the controlling valve so as to deliver the air pressure on the upper side of the diaphragm 36.

The inlet 43 of the valve chamber is connected by a pipe 50 with any suitable source of air under pressure, as a storage tank or the like. In the operation of the pump and coöperating mechanism thus far described it will be understood that in the reciprocation of the motor and at a predetermined point the slide valve parts would be in position to admit air under pressure through one of the ducts 9 or 10. Air from the storage tank or other supply will then pass through the pipe 50 past the valve 44, which is elevated in the normal position of the diaphragm 36, through the pipe 43, to the cylinder 1 on one side of the piston, operating the piston. As the valve plate of the slide valve is tripped through engagement with the particular pin 28 the air is admitted to the other side of the piston and the pumping operation thus secured. In the event the water supply in the pipe 47 is in excess of that used it is obvious that the air in the container or chamber 48 will be put under pressure with the effect to exert a corresponding pressure upon the diaphragm 36 and close the valve 44 to cut off the air supply to the motor proper. The pump is thus automatically governed in its operations as will be apparent.

Under some circumstances it will be further desirable to connect the pump rod leading into the well or other source of supply directly to the piston rod of the motor, and under other circumstances it would be advisable to provide means whereby the power of the motor may be augmented through leverage mechanism, and to accomplish the latter I prefer to utilize a particular form of equalizer or pumping lever illustrated. In this form I secure upon the base 27 of the motor a lever 51 secured at its inner end upon proper pivotal support rising from the base and divided at the outer end to present branch arms 52 which are

disposed on opposite sides of the pump rod 53 and connected thereto by arms 54 which extend from each arm 52 of the lever to a ball coupling 55 secured upon the pump 5 rod above the lever. An equalizing lever is also arranged in connection with the structure involving a rod like element 56 which, at the leverage point, may favor either side as desired, is offset through an angularly 10 related fulcrum section 57. The fulcrum portion is in the form of an elongated slotted section, through the slot 58 of which the lever 51 extends, and is pivotally mounted at 59. The free or outer end of the equalizing lever is also divided to present arms 60 disposed on opposite sides of the pump rod and an underlying section 61 carrying a roller 62 presenting a roller bearing for the pump rod in movement.

15 20 What is claimed is:

1. A pumping apparatus comprising a pump cylinder, a piston operating in said cylinder and provided with a hollow piston rod having a port opening adjacent the piston, a valve carried by said rod outside the cylinder and provided with stop means for limiting the throw thereof, and means actuated automatically by the movements of the piston for controlling said valve, said 25 controlling means having a relative, slight, free movement with reference to said valve.
2. An air motor including a piston, a piston rod having independent ports opening on opposite sides of the piston, a slide valve 30 secured to the rod below the pump cylinder, said slide valve comprising connected sections arranged on edge, through one of which the piston rod extends, the sections being formed with ports communicating 35 with the respective ports of the piston rod,

40 a valve plate movable in one of the sections of the slide valve and adapted to control the connections of the ports of one section with the ports of the other section, means for automatically operating the slide valve 45 in each direction, means arranged to trip and set in operation the automatic means in the respective reciprocating movements of the rod, and means for delivering air pressure to the slide valve. 50

3. The combination with a water pump, of an air motor including a piston, a piston rod having independent ports opening on opposite sides of the piston, a slide valve secured to the rod below the pump cylinder, 55 said slide valve comprising connected sections arranged on edge, through one of which the piston rod extends, the sections being formed with ports communicating with the respective ports of the piston rod, a valve 60 plate movable in one of the sections of the slide valve and adapted to control the connections of the ports of one section with the ports of the other section, means for automatically operating the slide valve in each 65 direction, means arranged to trip and set in operation the automatic means in the respective reciprocating movements of the rod, a pressure pipe having communication with the slide valve, a valve for controlling 70 said communication, and means governed by the water under pressure delivered from the pump for governing said controlling valve.

In testimony whereof I affix my signature 75 in presence of two witnesses.
